US00D333430S

United States Patent [19]
Reiseneder

[11] **Patent Number:** **Des. 333,430**

[45] **Date of Patent:** **** Feb. 23, 1993**

[54] **PILL BOX WITH VIBRATOR TIMER**

4,277,024 7/1981 Spector ..... 206/466 X
4,660,991 4/1987 Simon ..... 206/534 X
4,759,368 7/1988 Spanton et al. ..... D24/200 X

[75] **Inventor:** **Ingeborg Reiseneder, Chicago, Ill.**

Primary Examiner—Bernard Ansher

Assistant Examiner—Prabhakar Deshmukh

Attorney, Agent, or Firm—Milton S. Gerstein

[73] **Assignee:** **The Cloverline, Inc., Chicago, Ill.**

[**] **Term:** **14 Years**

[21] **Appl. No.:** **688,885**

[57] **CLAIM**

[22] **Filed:** **Apr. 22, 1991**

The ornamental design for a pill box with vibrator timer, as shown and described.

[52] **U.S. Cl.** **D9/418; D9/432;**
D9/417

DESCRIPTION

[58] **Field of Search** **D9/415, 418, 424, 432,**
D9/341, 337; D24/200; 206/528, 538, 530, 534,
535, 536, 461, 37.4, 828

FIG. 1 is a perspective view of a pill box with vibrator timer showing my new design;

FIG. 2 is a front elevational view thereof;

FIG. 3 is a front elevational view thereof with the pill box in partial open position shown for clarity of illustration;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
